UNITED STATES PATENT OFFICE.

WALTER E. HUENEFIELD, OF CINCINNATI, OHIO, ASSIGNOR TO THE HUENEFIELD COMPANY, OF CINCINNATI, OHIO.

HYDROCARBON-BURNER.

1,153,084.

Specification of Letters Patent. Patented Sept. 7, 1915.

Application filed December 28, 1914. Serial No. 879,362.

To all whom it may concern:

Be it known that I, WALTER E. HUENEFIELD, a citizen of the United States, and a resident of Cincinnati, in the county of Hamilton and State of Ohio, have invented certain new and useful Improvements in Hydrocarbon-Burners; and I do hereby declare the following to be a full, clear, and exact description of the invention, such as will enable others skilled in the art to which it appertains to make and use the same.

My invention relates to an improvement in hydrocarbon burners the object being to provide improved means for supporting and for lifting and lowering the combustion chamber member of the burner, and it consists in the parts and combination of parts, and in the details of construction as will be more fully explained and pointed out in the claims.

In the accompanying drawings, Figure 1 is a view in elevation of a burner or stove embodying my invention; Figs. 2 and 3 are views in section, one showing the combustion chamber member lowered onto the wick tube member and the other showing it elevated; Fig. 4 is a view in perspective of the winged frame for elevating the combustion chamber member, and Figs. 5, 6, 7 and 8 are views of modifications.

1 represents a base or frame of any construction, to which is secured the oil supply pipe 2 carrying the reservoir 3.

4 is the wick tube member composed of two concentric tubes separated to form a wick chamber between them, the lower end of said chamber being closed and the upper end open. The inner tube is open at both ends, and a nipple 5 is secured to the outer tube for connecting it with the oil supply pipe 2 in the usual manner, the nipple of course communicating with the wick chamber for supplying oil to the wick. The upper end of the outer wick tube is provided with an outwardly projecting flange 6 which is depressed somewhat forming a rib 7 at the upper extremity of said tube. The inner tube is provided with a depressed inwardly projecting flange 8, the inner edge of which is bent downwardly as shown so as to provide an enlarged bearing for the combustion chamber elevating frame which will be hereinafter referred to. A wick 9 is located within the wick chamber and is elevated and

lowered in the usual and well known manner. 55

A foot 9^a is secured to the wick tube member at a point opposite the nipple 5, and rests on the oil pipe 2 to assist the nipple 5 in supporting the wick tube member. 60

The two flanges at the upper end of the wick tube member constitute depressed seats for the lower ends of the perforated tubes 10 and 11, which are suitably spaced apart to form a combustion chamber between them. 65 This combustion chamber is located directly over the wick, and is surrounded by the casing 12 which is spaced from the outer perforated tube 10, and is open at its upper end, its lower end being provided with an inwardly projecting perforated flange, which stops short of the outer tube 10, thus leaving an air space between them. This casing 12 is in the form of a truncated cone and forms a chimney to protect the combustion 75 chamber from draft.

The upper end of the inner tube 11 of the combustion chamber member, is closed by a diaphragm 13 having a central opening, and its lower end is closed by a diaphragm 14 having perforations near its outer edge. These diaphragms, and particularly the lower one 14, are pressed in so that the end of the tube forms a marginal flange within which the upper end of the lifting frame 15 rests. 80

Located centrally within the wick tube member, is the combustion chamber lifting frame 15. This frame is composed of a plurality of wings 16 and 17, in the present 90 instance three, located equidistant apart, so that the wings form in effect a series of flues through which the air has free and unrestricted passage up through the wick tube member to the combustion chamber 95 member of the stove. In the present instance the frame is composed of two V-shaped pieces of metal, one wing of each V-shaped piece being secured together preferably by welding, so that the two wings 100 16 are of one thickness of metal and the other 17 of two thicknesses. The frame thus formed fits snugly within the depending flange 8 of the inner tube of the wick chamber, and is guided thereby, and each wing 105 16 and 17 is provided near its lower end with an integral outward extension 18 adapted to bear against the inner face of

the inner tube of the wick chamber and assist in holding the frame 15 upright and guiding it in its vertical movements.

The two members constituting the wing 5 17, are each provided with a downward extension 19, which are bent outwardly into inverted V-shape and form a saddle 20, which normally rests on the oil supply pipe 2. This saddle is located centrally under 10 the lifting frame preferably at right angles to the vertical axis of the latter, and the ends of its side members are rounded so that when the saddle which forms in effect a cam, is given a part rotation, it will ride up on 15 pipe 2 and when in its highest position which is acquired by a quarter turn, it rests on and is supported by said pipe.

21 is a handle secured to the saddle and projecting out beyond the wick tube member 20 so as to be readily accessible for turning the lifting frame. The handle is preferably a wire rod bent to conform to the shape of the saddle, so as to brace the latter at the top and prevent any spreading of 25 the two sides of said saddle. The lifting frame 15, when resting in its normal position on the oil supply pipe, rests sufficiently well down within the wick tube section of the burner, to permit the combustion chamber member to rest on the wick tube member. When however the lifting frame 15 is turned by the handle 21, its upper end engages the diaphragm 14 of the inner tube of the combustion chamber member within 30 35 the marginal flange on same, and elevates the said combustion chamber member sufficiently to expose the wick whereby the latter may be lighted. After the wick has been lighted, the frame 15 is turned so as to 40 lower the combustion chamber member onto the wick tube member.

When the burner is not in use, the combustion chamber member may be elevated and held so by the frame 15, thus preventing 45 the oil from working upwardly by capillary attraction from the wick, onto the tubes of the combustion chamber member and thus avoid to a large extent the odor of the oil and also obviate the smoke resulting from the combustion of oil on the tubes.

Instead of providing the wings with an outward extension 18 as above described, to assist the depending flange 8 of the inner tube of the wick chamber in guiding and 55 supporting the lifting frame in its vertical position, I may so construct the wings 16^a of the latter, that they bear against the inner face of the inner tube of the wick chamber throughout the greater part of the 60 length of the latter as shown in Fig. 5. This construction facilitates the insertion of the lifting frame into the wick tube, whereas in the previous construction the lifting frame has to be carefully guided so as to 65 enter the upper end thereof within the

flange 8 at the upper end of the inner wick tube. Again, in this construction one end only of each member 19^a of the saddle 20^a is rounded, which will be sufficient when the latter is turned always in one direction for 70 lifting it, and in the reverse direction for lowering it. Again, instead of making the saddle inverted V-shape as shown it may be inverted U-shape as at 20^b in Fig. 6, and instead of making this lower cam member 75 either an inverted V or U it may consist of a half saddle 20^c as shown in Figs. 7 and 8, rounded at one end as in Fig. 7 or a half saddle 20^d beveled as in Fig. 8.

It is evident that many other slight changes might be resorted to in the relative arrangement of parts shown and described without departing from the spirit and scope of my invention. Hence I would have it understood that I do not wish to 80 confine myself to the exact arrangement of parts shown and described, but

Having fully described my invention what I claim as new and desire to secure by Letters-Patent, is:—

1. In a hydrocarbon burner, the combination of a wick tube member, a combustion chamber member, a lifting frame located within the wick tube member and movable vertically for lifting the combustion chamber member, a cam member rigid with the lifting frame and coöperating with a support below and independent of the wick tube member, and a handle located below the wick tube member for rotating the cam member.

2. In a hydrocarbon burner, the combination of a wick tube member, a combustion chamber member, a lifting frame composed of a plurality of connected wings bearing at their outer edges against the inner face of the wick tube member and adapted to engage and lift the combustion chamber member and a cam member rigid with said lifting frame and coöperating with a part independent of the wick tube member for elevating the lifting frame.

3. In a hydrocarbon burner, the combination of a wick tube member, a combustion chamber member, a lifting frame passing vertically through the wick tube member terminating adjacent the top of the latter and adapted to be moved vertically to engage the combustion chamber member for lifting same, and a cam rigid with said lifting frame and coöperating with a support whereby when the cam member is turned in one direction on said support it will elevate the lifting frame and combustion chamber member, and when turned in the opposite direction will lower said parts.

4. In a hydrocarbon burner, the combination of a wick tube member, an oil supply pipe below the same, a combustion chamber member, a winged frame passing vertically

through said wick tube member, and engaging the combustion chamber member for elevating and lowering the same, and a saddle rigid with said winged frame for lifting and lowering the same, the said saddle resting on the oil supply pipe, and provided with a handle for turning the same.

5. A frame for lifting the combustion chamber of a hydrocarbon burner, composed 10 of two V-shaped metal sections secured together forming a three winged frame, a depending extension from said frame, and a cam member carried by said extension.

6. A frame for lifting the combustion 15 chamber of a hydrocarbon burner, consisting of two V-shaped sections secured together forming a three winged frame, two of which wings are of single thickness and one of double thickness, a depending extension 20 from said frame, a cam member carried by said extension and a handle connected with said cam member.

7. A frame for lifting the combustion chamber member of a hydrocarbon burner, 25 made of two V-shaped members secured together forming a three winged frame, a depending extension from said frame, a cam member integral with said depending ex-

tension and a handle secured to and bracing said cam member.

8. In a hydrocarbon burner, the combination of a wick tube member, a combustion tube member, a lifting device within the wick tube member and adapted to engage the combustion chamber member, and a saddle rigid with said lifting device and co-operating with a fixed support whereby when the saddle is turned in one direction it will elevate the lifting device and combustion tube member.

9. In a hydrocarbon burner the combination of a combustion chamber member, a wick tube member, having a straight inner guiding surface, a lifting frame within the wick tube member and engaging the latter 45 below the top thereof so as to be guided in its movements and maintained in vertical position, and means for turning the lifting frame.

In testimony whereof, I have signed this 50 specification in the presence of two subscribing witnesses.

WALTER E. HUENEFELD.
